PULVERIZER AND OTHER DEVICES

George Holt Fraser, Brooklyn, N. Y.

Application December 12, 1931, Serial No. 580,628

11 Claims.

(Cl. 83—45)

This invention relates to pulverizers and other devices, and aims to provide improvements therein.

Heretofore ring and roll pulverizers have had a rotatable ring having a peripheral crushing face disposed about a substantially horizontal axis and co-operating with a crushing roll within and eccentric of the ring and rotating on a substantially horizontal axis for crushing material between said faces, one of said parts being rotated and tractionally rotating the other, and the roll being radially and rockingly movable relatively to the ring to adapt itself to the material being crushed and to transmit spring or other crushing pressure toward the material, some such pulverizers have had axial inlet and discharge openings axially of the ring affording part of an endless current passage extending axially through the ring and returning externally of the casing enclosing the crushing parts, through which passage an external blower has caused air to flow axially through the ring for outblowing crushed material inwardly of and axially of the crushing parts, for discharging dust and grit axially of the crushing parts, the material being crushed being subject to such current during the crushing operation. One improvement applicable to such pulverizers is shown in my Patent No. 1,943,306 granted Jan. 16, 1934, on my companion application Serial No. 577,918 filed Nov. 30, 1931, as in part a continuation of my original application Serial No. 26,033 filed April 27, 1925, which in part pertaining to Air separators matured into Patent No. 1,834,095 dated Dec. 1, 1931, in which the ring is shown as having an axially inwardly compressive inclined traction face at each side of its crushing face and the roll is shown as having an axially outwardly compressive inclined traction face at each side of its crushing face, which faces wedgingly engage radially inwardly of said crushing faces to wedgingly tractionally grip the tractional faces of the roll between the tractional faces of the ring from radially inwardly of said crushing faces for insuring rotation of these parts from radially inwardly of said crushing faces without peripheral slippage, and inclinable bearings for the roll shafts are provided to permit the roll to be rocked relatively to the axis of the ring, in which application Serial No. 577,918 I have shown and claimed a tractionally driven rotative ring within a casing having a semi-circular or semi-spiral peripheral wall disposed about a horizontal axis and having a tangential peripheral current discharge outlet opening and a tangential peripheral current inlet opening, connect-

ed by a circuitous return current passage extended around a partition and crossed by dust interceptor means, the curved wall of the casing being spaced from the outer periphery of the ring, and fan blades being mounted on the outer periphery of the ring and revolved with it in the space between such periphery and such wall, for causing a fluid current to enter through said inlet and circulate outwardly of the outer periphery of the die around the casing and discharge tangentially through such outlet, for floating fine material around the casing outwardly of the outer periphery of the die and discharging it tangentially of the casing and outwardly of the outer periphery of the die into such passage, and for returning cleaned current through such interceptor means and such inlet tangentially, outwardly of the outer periphery of the die, to such blades, the blades being preferably eccentric of the chamber and adjacent the partition between its outlet and its inlet and rotated with and at the speed of the die, for eliminating passage of such current axially through the die, for avoiding molestation by such current of material within the die during pulverization.

In such mills a layer of granular material being crushed is held between the inner crushing face of the ring and the peripheral crushing face of the roll, and discharged at the sides of these, and when the ring is tractionally driven from the crushing face of the roll the torque is transmitted through this layer of granular material, which causes the granules to move between the crushing faces and cause wear and slippage therebetween during tractional drive of one from the other.

My present invention aims to provide improvements in pulverizers and other devices especially applicable to mills of the ring and roll type in which the ring and the crushing roll are the one driven and the other tractionally rotated from it, for improving their tractional engagement and axially positioning them, and for facilitating radial rocking of the roll, and for preventing escape of dust from the crushing faces to the bearings in which the roll is movably and rockingly mounted.

To this end in carrying out the preferred adaptation of my present improvements as applied to a ring having an inner annular concave crushing face having a cross-sectional shape of a segment of a sphere, I preferably provide radially outwardly of each side of its crushing face an annular outwardly flared or inclined material discharge male tractional driving face, and as applied to a crushing roll having a peripheral

crushing face in the shape of a segment of a sphere, I preferably provide radially outwardly of each side of said face an annular flaring or wedge shaped inclined material discharge interceptor female traction face corresponding to and for receiving and axially gripping, outwardly of and adjacent the zone of its interception of material discharge the adjacent inclined face of the ring radially outwardly of said crushing faces, for 10 compressively tractionally engaging the latter radially outwardly of said crushing faces, to drive one of said parts from the other from outwardly of and adjacent said zone, and thereby to prevent tractional slippage between them 15 from radially outwardly of said crushing faces, as well as to radially space their crushing faces when desired for controlling the fineness of material crushed between them; and when a plurality of crushing rolls is used I preferably provide one or 20 more of them with removable conical material interceptor and discharge, check flanges spaced axially of their crushing faces and radially outwardly of their crushing faces radially and outwardly projecting into the plane of the flared tractional faces of the ring for co-operating with its 25 side faces radially outwardly of its crushing face, to limit relative axial movement of the ring and roll from radially outwardly of their crushing faces; and I preferably provide compensating 30 rocking bearings in the shape of a segment of a sphere for rotatively and rockingly carrying the roll shafts from their bearing frames, and radially movable bearing members having sockets 35 preferably in the shape of a segment of a sphere for radially and axially moving and rockingly sustaining said bearings, and preferably having a lubricant inlet adjacent the periphery of said bearings and in communication with a preferably peripheral lubrication groove around the bearing 40 and one or more preferably radial lubricant ducts communicating from such groove to centrally of the interior of the bearing for introducing clean lubricant centrally thereof; and I preferably provide radially yielding expansive and contractive 45 cup shaped washers at each side of the bearing as a closure against escape of lubricant around the shaft during its rocking movements; and I preferably provide a radially and rockingly movable dust closure between the bearings and the outer 50 wall of the casing of the pulverizer, for permitting slight radial movement of the roll and rocking with the rocking movement of its shaft to prevent traverse of dust toward the bearing during such rocking movement, which closure preferably 55 has a portion in the shape of a segment of a sphere struck from the centre of the rocking bearing and rocking in a corresponding spherical cavity in a radially sliding dust guard sustained by and movable with and axially of the bearing 60 frame; and I preferably provide the vertical side wall of a crushing chamber with an inner slotted wall spaced inwardly of its plane and having in its outer face a radial slideway, and with a slotted outer wall having on its inner face a radial slideway opposite and spaced from said slideway, which inner and outer walls are preferably separately relatively removable, the outer wall preferably constituting a slotted plate against which 65 said sliding plate slides to close its slot, which slotted plate is preferably removably mounted on a slotted cup shaped plate affording within it a dust chamber between the roll and the slotted plate, in which I preferably provide radially movable and radially slidably contractive members, as 70 sliding and rolling dust plates encircling the shaft 75

and spring pressed toward the slotted plates to close their slots with sufficient axial pressure to frictionally sustain the members while permitting them to slide with the radial movement of the shaft, which plates preferably roll on a track 5 corresponding to the radial movement of the shafts, which track is preferably in the shape of an arc struck from the axis on which they are swung, the plates and tracks being preferably toothed to prevent revolution of the plates and 10 to assist in sustaining their weight to prevent their cutting into the shaft; and I preferably provide a rotary dust collar on the shaft and spaced between the slotted plates, between which it is axially movable with the axial movement of the shaft 15 to prevent direct flow of dust along the shaft, and I provide various other features of improvement which will hereinafter be more fully set forth with reference to the accompanying drawings, in which— 20

Fig. 1 is a vertical longitudinal section of a tractionally driven ring mill, showing the preferred form of my improved ring and rolls in side elevation;

Fig. 2 is a fragmentary plan view thereof, 25 partly broken away to show the upper roll in plan and one of the lower rolls and the ring in radial section, and to show the dust collector partly in horizontal section;

Fig. 3 is an enlarged fragmentary vertical 30 axial section of one of the upper bearings and its dust guards and roll;

Fig. 4 is a fragmentary transverse section thereof cut approximately on the line 4—4 and looking in the direction of the arrow, and 35

Fig. 5 is a fragmentary side elevation of one of the lower dust guards.

Referring to the drawings let A indicate a casing enclosing a chamber, B a crushing die therein, C the top crushing roll, C1 the front crushing 40 roll, C2 the rear crushing roll, D the feed supply or inlet, E the dust outlet, and F the drive, of a ring and roll pulverizer.

These parts may be of any usual or suitable construction for supplying material to be crushed 45 between the ring and rolls, rotating these to crush the material, and discharging crushed material from the discharge.

As shown the ring is a die having an inner concave annular crushing face b disposed about 50 a substantially horizontal axis, and the rolls are rotatable within the ring and each has a peripheral convex crushing face G in the form of a segment of a sphere and acting toward the concave face to crush material between these faces. 55

The ring and rolls are rotated in any suitable manner as by driving the shaft H of the top roll C from the pulley F and tractionally driving the ring B from the top roll C, and tractionally driving the lower rolls from the ring, each shaft H 60 being rotatably and rockingly mounted in its bearing I, which is radially moved by its bearing frame J and out-pressed by inner pressure springs K and outer pressure springs L adjusted by pressure screws M, to yieldingly sustain the roll toward the ring with a crushing pressure sufficient to crush the material on the inner face of the ring, and in the construction shown to vertically sustain the ring as a movable rotative die dragging on the top roll. 65

As shown in my said application Serial No. 577,918, the casing A has a curved semi-circular or semi-spiral peripheral wall spaced outwardly from the outer periphery of the ring and disposed around a horizontal axis, and encloses a 70 75

crushing chamber N within the ring and a semi-circular or semi-spiral blower chamber O without the ring, and has a tangential upper current effluent outlet P and a tangential lower current influent inlet Q, connected by a current passage R affording a grit well S for returning grit to the supply D, and crossed by a dust interceptor or filter T for intercepting dust floating through the passage and conducting it into a dust collector U for discharging such dust through the dust outlet E and returning cleaned air to the inlet Q, and the ring B is disposed eccentrically within and spaced from the casing and affords a partition between the pulverizing chamber and the blower chamber therein and rotary fan blades V around the ring revolve in the space between it and the casing A for causing a separating air current to enter through the inlet Q and flow around the casing to the outlet P and flow through the collecting passage R for out-floating fine material discharged from the ring, returning oversize to the ring and discharging dust.

As shown the bearings H are carried by swinging yokes W encircling the casing A and positioned around it by stop springs X around the pressure springs L, and by inner springs Y and outer springs Z adjacent the pressure spring, and all preferably in the plane of revolution of the ring, which yokes swing radially of the ring to press the rolls toward it and have slight transverse rocking action to yieldingly resist axial end thrust of the shafts of the rolls and to permit such shafts to rock radially slightly to adapt the rolls to variations in the depth of the material being crushed at one side or another of the ring, so that the rolls may rock slightly on their spherical peripheries during crushing, and rigidity will be avoided, universal flexibility being desirable in such devices to avoid crystallization of the shafts and prevent their breakage.

According to one feature of improvement my invention preferably provides the ring B constructed radially outwardly of its crushing face with a conical and preferably integral annular male outwardly flared axially expansive wedge shaped material discharge traction face a at each side of its concave crushing face b, and the roll C is constructed radially outwardly of its crushing face with a conical and preferably integral outwardly extended similarly inclined axially compressive annular wedge shaped material discharge interceptor female traction face c at each side of its peripheral crushing face G, which faces intercept discharge of material between them and the faces a, and engage and are wedged radially outwardly of said crushing faces into intimate gripping axial contact with the faces a, outwardly of the zone of said interception, as the ring and roll are pressed together, for fractionally rotating them from radially outwardly of said crushing faces at like peripheral speed for revolving one from the other from outwardly of and adjacent said zone, without slipping or tractional wear at their crushing faces and for consuming within the ring and roll of axial stress incident to their wedging engagement, and are preferably spaced and proportioned to slightly space the periphery of the roll from the adjacent inner crushing face of the ring from radially outwardly of said crushing faces, when limitation of extent of crushing is desired and to permit them to wear into each other to desired extent before the periphery of the crushing faces shall contact. These faces

axially guide the ring and roll and compel them to track on one another, but preferably permit the lower part of the ring to swing slightly axially to adapt itself to variations in the thickness of material being crushed against it.

According to another feature of improvement my invention preferably provides spaced axially removable outwardly flared rotary check plates material interceptor discharge d at each side of the peripheral crushing face of each lower roll and spaced inwardly of this face and extended outwardly obliquely at its sides and similarly inclined to and spaced axially from the inclined tractional faces of the ring and extended radially outwardly beyond these faces in line with the conical sides of the ring, for permitting axial movement of the latter and affording a discharge space between each side of the ring and the check plates and for axially rotatively and preferably wedgingly limiting or arresting axial swing of the lower part of the ring, which tends to spin on the convex periphery of the top roll or to travel toward either side. The plates d are preferably bolted against the side of their rolls by removable through-bolts, and one of them serves as a roll collar by clamping between it and the roll a shoulder e on the shaft H to hold the roll axially of its shaft. The plates d revolve at the same peripheral speed as the adjacent part of the ring, to minimize wear between them and centrifugally discharge crushed material between them and the ring, and are removable for renewal when necessary.

According to another feature of improvement I preferably provide compensating bearings I having the form of a segment of a sphere for swingingly carrying the radially and axially movable shafts H of the rolls from their bearing frames J and transmitting their radial thrust to these frames, preferably by forming the frames with a cylindrical clearance bore in which is formed a socket f having the shape of a segment of a sphere corresponding to the spherical periphery of the bearing I and receiving the latter for radially and axially positioning it while permitting it to swing or rock relatively of the frame to adapt itself to crushing stresses and to rotatively sustain the shaft without undue rigidity, and to rockingly transmit its radial and axial stresses to the frame to permit the latter to resist such stresses with the minimum of friction and without cramping incident to rocking or flexing of the shaft relative to the frame, and to close the outer ends of the bore I preferably construct the frame with annular male end faces g in the form of a segment of a sphere struck from the center of the bearing I, and rockingly engaged by a non-rotative outer thrust washer h and a non-rotative inner thrust washer i having female faces j in the shape of a segment of a sphere rockingly fitting against the faces g, which washers are carried by the shaft and movably close the end faces of the frame against ingress of dust or egress of lubricant during rotary or rocking movements of the shaft, the outer washer being held against the frame by springs k and a spherical thrust collar l between it and an outer arc shaped thrust collar m, and the inner washer being held against the frame by a spring m, and cup shaped washers n of expansive and contractile material being preferably mounted around the shaft inwardly of the washers h and i to yield and expand with the rocking of the shaft and to resist egress of lubricant around

it, which washers are preferably held in place by expansive springs *o* and by the outward pressure of lubricant between them.

The frames *J* are radially and usually radially and slightly axially movable relatively to the ring, and usually sustain a sliding dust guard *p* which slides over the shaft slot *q* in the side wall of the mill to close it during radial movements of the roll, and is movably mounted in the bearing frame to permit movement of the latter axially of the ring, and has cleared the shaft sufficiently to permit rocking movement of the latter, such clearance having been partially closed by the rotary collar *r* slidably keyed on the shaft and sustaining the washer *s* and a reciprocal washer sliding against the dust guard *p*, which washer tended to rock open with the rocking of the shaft, which according to one feature of my present improvement I preferably prevent by providing an oscillating washer *s* having an annular male surface *t* in the shape of a segment of a sphere rockingly engaging a similarly shaped female cavity *u* in the dust guard so that the closure between these may be complete during rocking of the shaft. The spring *m* reacts between the washers *s* and *t* to press them apart and keep them seated.

Heretofore the vertical side wall or cover *A'* of the casing *A* has been extended in a vertical plane spaced from the side of the ring *B* to facilitate discharge of crushed material from the latter, and has had a roll or shaft clearance inlet aperture spaced from the side of the roll, at the side of which the casing has been provided with axially spaced walls formed integrally in removable diametrically divided castings, the inner wall being inwardly of the plane of the side cover for enclosing between the inner and outer walls an annular clearance chamber around the shaft and a shaft slot for permitting radial movement of the shaft, within which chamber and spaced from which walls a rotary collar has been mounted on the shaft for affording circuitous communication from the crushing chamber into the clearance chamber and from the latter, instead of preventing such communication, or the side wall of the crushing chamber has had a single removable outer wall across its roll inlet aperture and removably fastened on its outer face, as a slotted cover *v*, the slot of which has been closed by the dust guard *p*, and according to one feature of my present invention as applied to the vertical side wall or cover of a crushing chamber having inner and outer walls enclosing a dust chamber at the inner side of this cover, I preferably provide and space inwardly of the plane of such cover radially movable and radially contactively slidable dust resistant walls for said crushing and dust chambers within the latter and in radially slidable overlapped contact with said inner and outer walls and extended across their slots, for completing the side walls of said crushing and dust chambers across said slots, and I preferably provide relatively axially separable and removable walls for this chamber, as by forming these walls separately instead of integral with the cover and accomplish this by providing at the inner side of the cover an additional similarly shaped cover *y* having an inwardly extended wall *w* and an inner slotted wall *x* encircling the shaft and preferably made of cup shaped stamped metal clamped between the side wall of the casing *A* and the usual roll cover *v*, so that the latter can be removed for access to the inner chamber, and

both can be removed for removal of the roll, and in the inner dust chamber afforded between them I preferably mount relatively slidable axially spaced similar fibre or other plates *z* fitting around the shaft and covering the slot in the plates and frictionally pressed against the latter by U shaped or other springs *a'* and affording between them a space in which I preferably mount a rotary dust collar *b'* which travels with the shaft and moves axially between the plates *z*, to prevent dust flowing along the shaft.

This construction is preferred for frictionally sustaining the weight of the fibre washer *z* for the shaft of the upper roll, but for the shafts of the lower rolls the radial movement of which approximates an angle of approximately 30° from the horizontal I prefer to rollingly sustain the weight of the fibre plates *c'* on tracks *d'* formed below them in the lower cup shaped cover *y*, and to prevent their rotation I preferably provide them with teeth meshing with notches *f'* in the cap, which afford between them spaces through which dust may drift from the inner chamber, for which purpose provision is made in the upper cap cover *y* by constructing its lower side with an outlet aperture *g'*. When the lower yokes swing from a fulcrum the track *d'* is preferably made in the shape of an arc struck from that fulcrum, and the lower fibre washer *c'* should have preferably a circular periphery concentric with the axis of their shafts respectively, and each washer should be movable radially of its shaft independent of the other washer to permit each to adapt itself to the rocking of the portion of its shaft which it engages, to permit which I preferably expansively press them apart with sufficient force to frictionally sustain part of their weight, for which I preferably interpose between them flexible expansive spiral springs *h'*.

In such devices the crushing pressure is exerted against one side of the bearing, and it is desirable that clean lubricant should be forced into the center of the bearing so that it may flow outwardly each way, and my invention preferably provides for this by providing the bearing frame with a forced lubricant inlet *i'* at its pressure side and at the center of its concave socket, and the spherical bearing I with a peripheral lubricant duct *j'* around and coincident with the spherical crown of its periphery and in juxtaposition to the duct *i'* for receiving lubricant from the latter and conducting it around the periphery of the bearing I, and I provide one or more radial ducts *k'* through the bearing communicating from its peripheral circumferential duct to centrally of its interior, the groove *j'* being wide enough to communicate with the duct *i'* throughout rocking movement of the bearing, and serving to conduct from the duct *i'* to one or another of the ducts *k'* for insuring entrance of lubricant centrally of the bearing during its rocking movement and regardless of whether or not the ducts *k'* are in line with the duct *i'*.

According to another feature of improvement my invention preferably provides the usual cheek plates *l'* at the sides of the die *B* with inwardly extended peripheral projections *m'* partly encircling and coinciding with the wall *x* of the inner dust chamber, and with outer dust outlets *n'* across their outer faces below the lower dust chambers for permitting dust to drift from the latter outwardly of the cheek plates, which pref-

erably are cast iron rings having the dust ducts *n'* on their outer faces and the usual bottom scrap well or outlet intermediate these ducts.

According to another feature of improvement 5 the outer end of the shaft *H* projecting beyond the collar *l* is closed against ingress of dust by an annular dust cap *p'* having an enlarged socket having an annular face *q'* spaced around the end of the shaft and having the shape of a segment of a sphere against which movably seats an annular washer *r'* fitting around the shaft and having a spherical portion *s'* movably fitting the face *q'* and moving thereon with movements of the shaft, which washer *r'* is spaced from the 10 thrust collar *l* by an annular spacer *t'* holding the washer toward the cap well to permit is movement in the enlarged portion of the latter.

According to another feature of improvement I preferably construct the bearing *I* of an outer 20 member *u'* having an outer periphery *v'* in the shape of a segment of a sphere around the crown of which it is formed with the peripheral groove *j'* inwardly of which it is formed with an inner rib *x'*, at each side of which it is formed 25 with an annular ball race *w'*, intermediate of which races it is formed with radially extended ducts *k'* communicating from the groove to intermediate the races for inletting lubricant centrally of the latter, and I space inwardly of such 30 race an inner member *y'* having a central rib *z'* between the ball races *a2*, and anti-frictional balls or rollers *b2* between these races to radially and axially rollingly resist or transmit thrusts from one race to the other, and I rockingly seat 35 the outer race in the spherical socket *f* of the frame *J*, and axially fix the inner race around the shaft *H*, so that the shaft may be rotatively and rockingly anti-frictionally sustained by the frame against radial and axial thrust, and the 40 lubricant forced into the duct *i'* of the frame may travel through the groove *j'* around the periphery of the outer race and through the duct *k'* and be delivered intermediate of the rollers or balls.

45 For resisting axial thrust in one direction the inner race is preferably mounted against a shoulder *c2*, and according to one feature of my invention for preventing its rotation and for resisting its axial movement in the other direction I preferably form the outer corner of it with a notch *d2* and the shaft with a keyway *e2*, the bottom faces of the notch and keyway being segments of a circle struck from the same centre, between which faces I preferably provide an arc shaped 50 key *f2*, which rocks into the arc shaped space between the shaft and the inner race and engages the corner of the latter to prevent the race from turning on the shaft and engages the arc shaped faces of the shaft and race to prevent it from 55 moving axially of the shaft, but is low enough to permit it being rocked around the exposed portion of the arc shaped bottom of the notch for permitting its removal from the cavity between the race and the shaft, which key is preferably 60 prevented from loosening by a spring or other ring *g2*.

According to another feature of improvement I preferably prevent rotation of the outer race by mounting in the groove *j'* a half round ring or 65 spring or wire clip *h2* having outwardly and inwardly extended rocked or pivotal rotation resistant or bent ends *i2* engaging the diametrically opposite ducts *k'* and diametrically opposite sockets *j2* in the parting between the body and cap 70 of the bearing frame, for resisting rotation of the

outer race, while permitting the outer race to rock freely with its shaft in the direction of the crushing stress.

In operation material to be pulverized is fed 5 to the inlet *B* and is centrifugally held on the inner face of the die by revolving with it until the material passes the crushing faces of the rolls, which pulverize it and push it off past the sides of the ring so that it flies from the inner crushing chamber to the outer blower chamber. The 10 rotary fan whirls the air and the dust fine enough to float in it around the die to the outlet *P* through which it passes with a downward curve 15 into the grit well *S* for centrifugally precipitating large particles in this well and returning them to the feed inlet. The air rises from the well *S* through the passage *R* into the chamber *U* from which it passes through the filter *T* which intercepts dust floating in it and permits the cleaned 20 air to return through the tangential inlet *Q* to the blower chamber, the dust being conducted from the return air by the dust conduit *E* so that the air is continuously circulated through an endless path the lower leg of which extends peripherally around the die and its crushing chamber and 25 crushing elements and the upper leg which affords a circuitous passage between the outlet and the inlet and encloses a precipitation chamber for gravity return of oversize, a separating chamber for cleaning the current, a dust outlet for discharging the dust and a return passage for returning the cleaned current to the tangential 30 inlet.

When the die is a freely movable revolving ring it is radially positioned by the crushing rolls 35 which are positioned by their springs, and it is axially positioned by the male and female tractive faces of the top roll and axially limited by the check plates on the lower rolls against its tendency to axially swing or spin on the periphery 40 of the top roll, and these wedge faces afford radially outwardly of the crushing faces a wedging tractive engagement between the die and the top roll for insuring rotation of one from the other without slippage and without tractive 45 wear of their crushing faces, and for limiting the approach of their crushing faces.

The spherical rocking bearings for the roll shafts will permit their shafts and bearing frames to rock relatively to one another and their shafts 50 to rock to compensate for inequalities in their wedging faces or for unequal distribution on the inner face of the ring of the material being crushed by the rolls.

The inlet apertures through the inner and 55 outer walls of the crushing chamber will be radially slidably closed by the radially slidably contactive walls *z* between and divergently pressed against the inner and outer walls respectively, for contactively slidably resisting communication 60 from the crushing chamber to the clearance chamber and from the clearance chamber to any dust guard provision outside of the walls of the crushing chamber, and the presser means *a'* between the contactive walls *z* will axially space 65 these from outwardly of and around the collar *v'* spaced between them, for permitting rotation of this collar inwardly of the presser means.

The rotary collars and sliding plates around the shaft will be accessibly enclosed and protected 70 in this chamber, and the sliding and oscillatory plates between the roll covers and the bearings will adapt themselves to rocking of the shaft while closing the variable space between its roll and the bearing frame.

Grease under pressure will be forced around and into the center of the oscillating bearing and old grease will be forced from each side of this bearing and retained around it by the flexible 5 cup washers filling the space between the shaft and the bearing frame.

The spherical cavity in the bearing frame will axially and radially rockingly position the outer ring of the bearing, and the balls between the 10 outer and inner rings will axially and radially position the inner ring, which will radially and axially position the shaft in both against axial thrust in either direction when circumferentially and axially keyed to the shaft by my axially 15 thrust resistant rocking key at one side for holding against the out thrust shoulder on the shaft at the other side.

It will be seen that my invention provides improvements which can be variously and advantageously availed of in whole or in part, and it will be understood that the invention is not limited to the particular details of construction, arrangement, or combination of parts, set forth 20 as constituting its preferred form, since it can be availed of in whole or in part according to such constructions, arrangements, or combination of parts, as circumstances, or the judgment of those skilled in the art may dictate, without departing 25 from the spirit of the invention.

30 My peripheral lubricant groove and radial duct may be applied to the outer ring of any ball bearing and any rockable anti-friction bearing may be used with my improvements, whether the portion of the outer ring in the shape of a segment of a 35 sphere is its inner or outer periphery, and whether the cross-sectional contour of the inner and outer races and corresponding curvature of the anti-frictional rolls between them, are such as to afford oscillation as well as rotation of the shaft with 40 anti-frictional axial thrust resistance.

My radially slidable plates and collars may have arc shaped faces in the form of a segment of a cylinder for engaging similar faces on the parts against which they slide, and spherical faces 45 for engaging similar faces on the rotative parts which engage them to sustain or slide them.

The key $f/2$ utilizes the rocking principle of the Woodward key and the rocking limitation principle of the Hylo key and improves these by 50 adapting them to rotative resistance of a ring having the minimum possible key seat instead of being weakened by a through key seat, and improves them to utilize them for axial thrust resistance in one or both directions, preferably in 55 both directions as shown in Fig. 3 by grooving the inner ring to a curvature corresponding to that of the inner wall of the notch or key seat $d/2$, and forming the key $f/2$ with a concave edge fitting and engaging both sides of the convex inner wall 60 in the ring, so that the ends of the key resist axial movement of this wall in either direction when the free end of the key is locked by passing over it the sleeve or ring $g/2$, which ring when disengaged permits the key to be rocked out.

65 The bearing and dust guard and leakage prevention constructions herein shown and described are not claimed in the present application, but are claimed in a divisional application filed July 20, 1935, Serial No. 32,423.

70 What I claim is:

1. In a pulverizer comprising, support means, a 75 rotatable annular crushing die thereon, having side discharge faces and an inner annular crushing face, a rotatable crushing roll within and eccentric of said die, having a peripheral crushing

face co-operable with said inner face, for crushing material thereagainst, said die and roll adapted to be tractively rotated one from the other, supply means adapted to supply material to be crushed to said inner face, and rotary drive means adapted to rotate one of said rotatable parts; the combination therewith of axially compressive tractive drive means radially outwardly of said crushing faces, adapted to rotate one of said rotatable parts from the other from radially outwardly of said crushing faces, comprising a material discharge, conical male traction face, at each side of and rotatable with said die, extended divergently outwardly around said inner face, and adapted to divergently discharge crushed material therefrom, and a material interceptor, conical female traction face at each side of and rotatable with said roll, extended divergently outwardly beyond said crushing faces and tractively engaged with the adjacent of said discharge faces radially outwardly of said crushing faces, and adapted to intercept said discharge adjacent said engagement, said discharge and interceptor faces of like conicity, and said female faces rotatable with and in axially compressive tractive engagement 25 with said male faces radially outwardly of the zone of said interception, and adapted to tractively rotate one of said rotatable parts from the other with minimum molestation from said discharge. 30

2. In the pulverizer specified in claim 1, said crushing faces being radially spaced from one another and adapted to granulate said material between their spaced faces, and said material interceptor conical female traction faces being outwardly of said inner face and extended radially outwardly across said space, and adapted to intercept said discharge axially of said space, and being radially resistantly axially compressively 40 tractively engaged with said material discharge male traction faces radially outwardly of said space, said male and female faces adapted to tractively interengage radially outwardly of said space and said interception, and to radially space 45 said crushing faces from, and to tractively rotate one of said rotatable parts from the other from, outwardly of said space and said interception, and with minimum molestation from said discharge. 50

3. In the pulverizer specified in claim 1, said crushing faces being axially concave and convex respectively, and having maximum central and minimum side diameters, and said discharge and interceptor conical faces being tractively interengaged adjacent the zone of said interception and radially outwardly of said inner diameters, and adapted to axially compressively tractively 55 rotate one of said rotatable parts from the other from adjacent said interception and from outwardly of said inner diameters, with minimum molestation from said discharge. 60

4. In the pulverizer specified in claim 1, said die and said roll being one radially sustained from the other, and said material interceptor 65 conical faces being radial sustainer, axially compressive, traction faces radially outwardly of said inner face, and in radial support and tractive drive engagement outwardly thereof with said material discharge faces adjacent said interception, and adapted to radially sustain and axially compressively tractively rotate one of said rotatable parts from the other from radially outwardly of the zone of said crushing and with minimum molestation from said discharge. 75

5. In the pulverizer specified in claim 1, said die being the driven and said roll being the driver rotatable part, and said rotary drive means being adapted to rotate said roll, and said material discharge male conical faces at each side of said die being tractionsally driven faces radially outwardly of said inner face, and said material interceptor female conical faces being tractionsal driver faces radially outwardly of said peripheral face, and axially compressively drivingly engaged with said driven faces adjacent said interception and radially outwardly of said crushing zone, and adapted to rotate said die from said roll from radially outwardly of said crushing faces and outwardly of said interception, with minimum molestation from said discharge.

6. In the pulverizer specified in claim 1, said die and roll being rotatable around substantially horizontal axes, and adapted to horizontally discharge crushed material from between said crushing faces, and said material interceptor female conical faces being extended divergently outwardly across the zone of said horizontal discharge and axially compressively tractionsally engaged with said material discharge male conical faces outwardly of and adjacent said zone, and adapted to intercept and diverge said discharge adjacent said engagement, and to tractionsally rotate one of said rotatable parts from the other from adjacent said interception and divergence and with minimum molestation from said discharge.

7. In the pulverizer specified in claim 1, said die and roll being rotatable on substantially horizontal axes, and said die being vertically sustained by said roll, and said material interceptor female conical faces being die sustainer, axially compressive, tractionsal drive faces, outwardly of said peripheral faces, and said material discharge male conical faces being die sustainer tractionsal drive faces outwardly of said inner face, said tractionsal faces being interengaged adjacent said interception and radially outwardly of said crushing faces, and adapted to vertically support said die from said roll, and to tractionsally rotate one of said rotatable parts from the other, from outwardly of said interception and with minimum molestation from said discharge.

8. In the pulverizer specified in claim 1, said die and said roll being rotatable around substantially horizontal axes and said roll being adjacent the upper part of said die, and said material interceptor, axially compressive, female conical faces, and said material discharge, male conical faces, being wedgingly interengaged above said roll and above and adjacent the zone of said interception, and a lower roll within and eccentric of a lower portion of said die, having a peripheral crushing face downwardly pressed against said inner face below said interceptor, and adapted to thereby downwardly press said die from below said zone

toward said first roll, and thereby from below the latter to intensify said engagement with minimum molestation from said discharge.

9. In the pulverizer specified in claim 1, said die and roll rotatable around substantially horizontal axes and said roll disposed adjacent the upper part of said die, and a rotatable lower roll within and eccentric of said die, below said upper roll and above and in operative relation to a lower portion of said material discharge conical faces, having at each side of said lower roll a die interceptor female conical face, extended radially outwardly beyond said inner face and across the adjacent one of said material discharge male faces, of similar conicity to the latter, and adapted to rotatably engage therewith, and thereby to rotatably resist axial movement of the lower portion of said die from radially outwardly of the lower portion of said inner face and from below said upper roll.

10. In a pulverizer comprising, support means, a rotatable and axially movable annular crushing die carried thereby, having divergently outwardly flared conical material discharge side faces and an intermediate inner annular crushing face, a rotatable crushing roll within and eccentric of said die, having a peripheral crushing face co-operable with said inner face, for crushing material thereagainst, supply means adapted to supply material to be crushed to said inner face, and rotary drive means adapted to rotate one of said rotatable parts; the combination therewith of a material interceptor conical annular rotatable check face at each side of and rotatable with said roll, spaced axially from and extended radially divergently outwardly opposite and across the adjacent one of said discharge faces, of similar conicity to the latter, rotatable with said roll, and adapted to rotatably diverge said discharge between it and said discharge face during normal movement of said die, and to rotatably engage said discharge face radially outwardly of said inner face, and then to intercept said discharge and check axial movement of said die, upon abnormal axial movement thereof, and thereby to resist said abnormal movement with minimum molestation from said discharge.

11. In the pulverizer specified in claim 10, said material interceptor conical face at each side of said roll being extended from radially inwardly of the peripheral crushing face of said roll divergently outwardly at an axially spaced distance therefrom, and radially past the peripheries of said peripheral and inner faces and across said discharge face at an axially spaced distance therefrom, and adapted upon wear of said peripheral face to permit said conical discharge face to enter the space between it and said conical interceptor face, and thereby to absorb said wear with minimum interference of said conical faces with said absorption.

GEORGE HOLT FRASER.
